PLUNGER PUMP

Richard C. Mason, Tulsa, Okla., assignor of one-half to
M. J. McNulty, Jr., Tulsa, Okla.

Application September 13, 1956, Serial No. 609,630

4 Claims. (Cl. 103—158)

This invention relates to deep well plunger pumps of the traveling barrel type wherein the barrel moves with the sucker rods over a fixed plunger unit that is anchored within the lower end of the well tubing.

The usual pump of this character includes a standing valve on the upper end of the plunger unit and a traveling valve on the upper end of the traveling barrel, both of which operate responsive to flow through the seats therefor as the well fluid flows into and out of the working barrel. The traveling valves usually operate satisfactorily because of the pressure discharge of the well fluid from the working barrel, but the standing valves are subject to sanding up and may not fully open or close, so that the pump does not operate to take in the full capacity of the working barrel and to assure full displacement thereof through the well tubing.

It is, therefore, a principal object of the present invention to provide a deep well plunger pump of the traveling barrel type wherein the plunger body cooperates with the pull tube to constitute a standing valve which is positive in operation and the action of the working barrel assures full opening and closing movement of the plunger in effecting its function as a standing valve.

A further object of the invention is to provide a plunger pump of the traveling barrel type wherein the plunger is equipped with positive and wear resistant sealing elements which are not so easily affected by the sand or corrosive elements of the well fluid.

Another object of the invention is to provide a plunger pump of the traveling barrel type which is of simple and inexpensive construction and which is capable of taking in and discharging the maximum capacity of the traveling barrel on each stroke thereof.

Other objects of the invention are to provide a pump structure that will not sand up, become gas locked, or be affected by magnetism.

A further object is to effect agitation in wells producing gas and to cause the gas to help in pushing the oil up and into the traveling barrel.

In accomplishing these and other objects of the invention as hereinafter pointed out, I have provided improved structure, the preferred form of which is illustrated in the accompanying drawings wherein:

Fig. 1 is a perspective view of a deep well plunger pump installation wherein the pump embodies the features of the present invention, the traveling barrel of the pump being shown in vertical section to better illustrate the plunger unit.

Fig. 2 is an enlarged vertical section through the plunger unit of the pump on the line 2—2 of Fig. 1 and showing the plunger in position to allow the flow of fluid from the upper end of the pull tube through the plunger and into the traveling barrel at the start of the upstroke of the traveling barrel.

Fig. 3 is a similar section but showing the traveling barrel on the downstroke and the plunger in seated position for trapping the well fluid in the traveling barrel.

and assuring full discharge thereof through the traveling valve into the well tubing on the upstroke of the sucker rods.

Fig. 4 is a perspective view of the plunger, the guide stem and the plunger seat bushing, the parts being shown in disassembled spaced relation.

Fig. 5 is a perspective view of the upper end of the pull tube and the fluid outlet coupling which also constitutes support for the plunger valve seat bushing.

Fig. 6 is an enlarged fragmentary vertical section of the lower portion of the plunger, the plunger seat and the sealing ring, the plunger being shown in unseated position for flow of well fluid from the pull tube through the axial fluid passageway of the plunger.

Fig. 7 is a cross section through the plunger particularly illustrating one of the sealing rings therefor.

Fig. 8 is a vertical section of a modified form of plunger piston.

Referring more in detail to the drawings:

20 1 designates a deep well plunger pump constructed in accordance with the present invention. The pump includes a plunger unit 2 which is anchored within the lower end of the well tubing 3 by means of a hold-down body 4 seated in a hold-down shoe 5 that is affixed to the lower end of the well tubing 3. The pump also includes a traveling barrel 6 that is reciprocated upon and over the plunger unit by means of a string of sucker rods 7. The sucker rods 7 extend downwardly through the well tubing 3 and are operated at the top of the well by any suitable pumping jack or other power means (not shown). Connected with the hold-down body and extending upwardly within the well tubing is a pull tube 8. The lower end of the pull tube is connected through the hold-down body with a pipe section 9 that extends into the well fluid, as in conventional practice. The upper end of the pull tube 8 has a reduced threaded extension 10 for mounting a coupling 11, the upper end 12 of which is of reduced diameter and provided with a plurality of outlets 13 in the wall thereof for flow of well fluid, as later described. The inner periphery of the coupling at the upper end thereof has an internal annular shoulder 14 encircling internally threaded portion 15 for containing a plunger seat bushing 16.

The plunger seat bushing 16 has an externally threaded body 17 encircled at its upper end by an annular flange 18 of larger diameter to form an annular shoulder 19. The seat bushing 16 is threaded into the upper end of the coupling 11 to engage the shoulder 19 with the internal shoulder 14 of the coupling 11 to form a rigid support for a plunger guide stem 20. The upper face 21 of the seat bushing 16 is substantially flat and provided with an annular groove 22 to seat an O ring 23. The O ring 23 is formed of resilient material, preferably one of the synthetic rubbers that is unaffected by petroleum fluids. The O ring is preferably of circular cross section and seats firmly within the annular groove 22 for sealing contact by the lower end of the plunger or piston element 24, as later described.

The seat bushing 16 has an axial opening 25 having internal threads 26. The plunger guide stem 20 comprises a section of rod having threaded ends 27 and 28 to respectively engage within the threaded opening 25 and to mount a plunger stop 29.

The plunger element 24 includes a sleeve-like core 30 of larger inner diameter than the exterior diameter of the stem 20 to form an annular fluid passageway 31 opening therethrough for transfer of well fluid from the lower through the upper end of the plunger element 24, as later described. The lower end of the core 30 has an annular flange 32 for seating one end 33 of a cylindrical body 34 thereon. The upper end of the core 30 projects through the cylindrical body 34 and is exteriorly threaded

to mount a retaining nut 35 for securing the cylindrical body 34 of the plunger element against the flange 32. The stop 29 comprises a wing nut 36 threaded on the upper end of the guide stem 20 with the wings 37 turned downwardly, as shown in Figs. 2 and 3, to engage the nut 35 and limit upward movement of the plunger element 24 when the plunger element is moved away from the seat bushing 16 on the upstroke of the traveling barrel 6. On the downstroke of the traveling barrel the plunger element 24 is shifted into contact with the sealing ring 23 so that the well fluid previously passed through the plunger is trapped for forced discharge into the well tubing 3.

The guide stem 20 is preferably provided with pins 20' that extend therethrough and have ends projecting into contact with the core 30 to center the core and maintain passage uniformly about the guide stem.

In order to seal the plunger element 24 with respect to the traveling barrel 6 and prevent leakage of the well fluid therebetween, the cylindrical body 34 of the plunger element 24 has a plurality of circumferential grooves 38 spaced apart along the length thereof for sealing rings 39. The sealing rings 39 are of the expansion type and are preferably formed of metal having a close fit within the grooves and capable of expanding into sealing contact with the traveling barrel 6. The plunger element 24 is preferably of slightly flexible material to expand a small amount with load on the upstroke to flex the rings 39 so that they set to the wall of the traveling barrel 6.

The traveling barrel 6 comprises a sleeve-like body 40 having a sliding fit upon the body 34 of the plunger element 24 and of a length relative to the plunger unit 2 to provide the length of the pump desired for a particular pumping job. The upper end of the traveling barrel 6 carries a valve seat ring 41 that is retained thereon by a valve cage 42 containing a ball valve 43 which constitutes the traveling valve of the pump. The lower end of the traveling barrel carries a bushing 44 that provides a guide for the barrel on the pull tube 8, as shown in Fig. 1. The cage is connected to the string of sucker rods 7 in the usual manner.

In assembling the pump, the pull tube 8 is connected with the hold-down body 4, the bushing 44 for the lower end of the traveling barrel 6 is sleeved over the pull tube 8, and the coupling 11 is connected with the upper end of the pull tube 8. The seat bushing 16 is threaded into the upper end of the coupling 11 so that the flange 18 thereon makes contact with the internal annular shoulder 14. The guide stem 20 is threaded into the seat bushing 16 and the O ring 23 is inserted within the annular groove 22. The body 34 of the plunger element is mounted on the core 30 and secured in contact with the lower flange 32 of the core by the nut 35. The plunger assembly is then placed over the guide stem 20, after which the wing nut 36 is fixed to the upper threaded end of the guide stem 20 and preferably retained by a cotter pin 45. The traveling valve seat ring 41 of the working barrel is applied to the upper end of the working barrel and the ball valve 43 is placed in the cage 42 and the cage 42 is secured to the upper end of the traveling barrel to retain the valve seat ring 41 and the ball valve 43 to complete assembly of the pump.

The assembled pump is then connected with the first of the sucker rods 7 and is lowered through the well tubing 3 in accordance with the usual practice until the hold-down body 4 seats within the hold-down shoe 5 to anchor the plunger unit 2 of the pump.

Assuming that the sucker rods 7 are connected with a suitable power at the top of the well (not shown), the rods 7 are reciprocated within the tubing 3 to effect an up-and-down movement of the traveling barrel 6 over the plunger unit 2. The sealing rings 39 on the plunger element effect a substantial frictional contact with the working barrel 6 so that the plunger element is shifted between

the seat bushing 16 and the stop 29 responsive to reciprocation of the working barrel 6. For example, assuming that the working barrel 6 is on the upstroke, the initial movement thereof shifts the plunger or piston element upwardly to unseat the lower end thereof from contact with the O ring 23 and engage the stop 29. The plunger element is retained in contact with the stop 29 throughout the upstroke of the traveling barrel. During this movement, the well fluid is drawn through the strainer section 9 and pull tube 8 for discharge through the openings or outlets 13 in the wall of the coupling 11 and upwardly through the annular passageway 31 for discharge into the working barrel 6. On the downstroke, the initial movement of the traveling barrel 6 effects seating of the plunger element on the sealing ring 23 to close the bottom outlet to the passageway 31 and trap the well fluid in the working barrel. As the working barrel moves downwardly, the trapped fluid is displaced by lifting the traveling valve 43 and discharging into the well tubing through the outlets of the traveling valve cage 42. On the next upstroke the standing valve 43 seats and the plunger element is lifted by frictional contact thereof with the working barrel so as to draw another charge of well fluid into the working barrel and effect lift of the previously discharged well fluid within the well tubing.

Fig. 8 shows a modified form of plunger piston 46 wherein the core-sleeve 47 carries a series of cups 48 separated by spacers 49, in accordance with conventional pump pistons, if this type of sealing ring is desired. A pump equipped with the piston of Fig. 8 operates in a manner similar to the pump as above described.

From the foregoing it is obvious that I have provided a plunger pump wherein action of the traveling barrel effects a positive movement of the plunger element so as to assure full opening movement thereof in one direction of the traveling barrel and positive closing thereof in the opposite direction of the traveling barrel. It is also obvious that the expansion rings 39 provide an effective seal between the traveling barrel and the plunger element, consequently the well liquid drawn into the working barrel does not leak back into the well, but is discharged into the well tubing to be lifted upon the next upstroke of the traveling barrel. It is also obvious that the pump is of simple and relatively inexpensive construction and is constructed so that it is comparatively free of sanding up difficulties.

What I claim and desire to secure by Letters Patent is:

1. A pump including a plunger unit and a traveling barrel reciprocable upon the plunger unit to draw well fluid thereinto and lift well fluid when the traveling barrel is reciprocated in one direction and to displace well fluid from the traveling barrel when the traveling barrel is reciprocated in the opposite direction, wherein the plunger unit comprises a pull tube for conducting flow of well fluid from the well to the traveling barrel, a coupling on the upper end of the pull tube and having lateral outlet for the well fluid, a seat member carried on the upper end of the coupling, a guide stem fixed to and extending upwardly from the seat member, a piston element having an axial passageway for loosely mounting the piston element on the guide stem and to pass the well fluid therethrough, a valving part on the piston element and encircling the axial passageway for engaging the seat member to close flow of well fluid through said axial passageway in one position of the piston element, and a stop on the upper end of the guide stem to limit upward movement of the piston element from the seat member, said piston element having frictional contact with the traveling barrel for effecting said valving action of the piston element responsive to movement of the traveling barrel in said respective directions.

2. A pump including a plunger unit and a traveling barrel reciprocable upon the plunger unit to draw well fluid thereinto and lift well fluid when the traveling barrel is reciprocated in one direction and to displace well fluid

from the traveling barrel when the traveling barrel is reciprocated in the opposite direction, wherein the plunger unit comprises a pull tube providing a duct for conducting flow of well fluid from the well to the traveling barrel, a coupling on the upper end of the pull tube and having side outlets for the well fluid, a seat member on the upper end of the coupling, a guide stem supported by and extending upwardly from the seat member, a piston element adapted to seat upon the seat member and having an axial passageway for loosely mounting the piston element on the guide stem and to pass well fluid therethrough when the piston element is raised from the seat member, said seat member being adapted to close flow through said axial passageway when the piston element is engaging the seat member, and a stop on the upper end of the guide stem to limit upward movement of the piston element from the seat member, said piston element having frictional contact with the traveling barrel for effecting said valving action of the piston element responsive to movement of the traveling barrel in said respective directions.

3. A pump including a plunger unit and a traveling barrel reciprocable upon the plunger unit to draw well fluid thereinto and lift well fluid when the traveling barrel is reciprocated in one direction and to displace well fluid from the traveling barrel when the traveling barrel is reciprocated in the opposite direction, wherein the plunger unit comprises a pull tube providing a passage for conducting flow of well fluid from the well into the traveling barrel, a coupling on the upper end of the pull tube and having lateral outlet for the well fluid, a seat member carried by the upper end of said coupling and having an annular groove, an O ring in the groove, a guide stem extending upwardly from the seat member in centered relation with respect to the O ring, a piston element having an axial passageway for loosely mounting the piston element on the guide stem and to pass the well fluid therethrough, a valving part on the lower end of the piston element and encircling the axial passageway for en-

gaging the O ring to close flow of well fluid through said passageway of the piston element, and a stop on the upper end of the guide stem to limit upward movement of the piston element from the seat member, said piston element having frictional contact with the traveling barrel for effecting said valving action of the piston element responsive to movement of the traveling barrel in said respective directions.

4. A pump including a plunger unit and a traveling barrel reciprocable upon the plunger unit to draw well fluid thereinto and lift well fluid when the traveling barrel is reciprocated in one direction and to displace well fluid from the traveling barrel when the traveling barrel is reciprocated in the opposite direction, wherein the plunger unit comprises a pull tube providing a passage for conducting flow of well fluid from the well to the traveling barrel, a coupling on the upper end of the pull tube and having lateral outlet for the well fluid, a seat member carried by the upper end of the coupling, a guide stem extending upwardly from the seat member, a piston element having an axial passageway for loosely mounting the piston element on the guide stem and to pass the well fluid therethrough, a valving part on the lower end of the piston element and encircling the axial passageway for engaging the seat member to close flow of well fluid through said passageway in one position of the piston element, a stop on the upper end of the guide stem to limit upward movement of the piston element from the seat member, and expansion rings on the piston element having frictional contact with the traveling barrel for effecting movement of the piston element responsive to initial movements of the traveling barrel in said respective directions.
